UNITED STATES PATENT OFFICE.

HENRY J. HYER, OF UNADILLA, NEW YORK.

POTATO-PARING MACHINE.

SPECIFICATION forming part of Letters Patent No. 362,009, dated April 26, 1887.

Application filed July 17, 1886. Serial No. 208,279. (No model.)

To all whom it may concern:

Be it known that I, HENRY J. HYER, a citizen of the United States, residing at Unadilla, in the county of Otsego and State of New York, have invented a new and useful Improvement in Potato-Paring Machines, of which the following is a specification.

In my improved potato-paring machine the potatoes are placed within the paring-cylinder, and are kept wet with water while the skin is being removed. The cylinder has means provided for the charging and discharging of the potatoes, and to enable their-ready inspection while being pared.

15 My invention particularly consists in certain details of construction of the machine, which will be first described with reference to the accompanying drawings, and then specifically pointed out in the claims.

20 In said drawings, Figure I is an elevation of one end of the potato-paring machine. Fig. II is an elevation of the other end thereof. Fig. III is a side elevation, the cover being shown in section. Fig. IV is a vertical axial section. Fig. V is a plan view to a larger scale of one of the plates of the paring-cylinder. Fig. VI is an inside view of one of the cylinder-heads.

25 The shaft 1, on which the paring-cylinder is mounted, is journaled at its ends in the frame 2, which may stand upon the floor, as shown. Between the sides of the frame is supported a trough, 3, for containing water, which rests on cross-braces 4 of the frame 2, as shown in Figs. III and IV. A two-part shield or cover, 5, opening at top, is hinged at the sides of the trough, and, surrounding the paring-cylinder, prevents water and gratings from being thrown outward and away from the machine.

30 The paring-cylinder is made up of a number of rings or sections, 6 7 8 9. The sections 6 and 9 are fixed to their adjacent ends or heads 10 11 of the cylinder. The head 10 is fixed by screw or otherwise rigidly to the shaft 1. The 35 section 8 is also made rigid with said shaft, being supported therefrom by spokes or arms 12. The head 11, however, runs loosely on the shaft 1, and the section 7 is rigidly connected with section 9 on said head by means 40 of arms 13. The sections 6 and 8 are thus adapted to move together, and the sections 7

and 9 together. The sections 6 and 8 move with the shaft when operated by the crank 14; but the sections 7 and 9 are turned in the opposite direction by means of the reversing-gear shown in Fig. I, in which 15 is a gear-wheel rigid with the shaft 1. 16 is a pinion journaled on a stud projecting inwardly from the frame 2 and gearing with the wheel 15, and 17 is a rack internally toothed and rigid 55 with the head 11 of the cylinder, and consequently with the sections 7 and 9. In this manner the alternate sections of the cylinder are forced to rotate in opposite directions.

50 In order to support the weight of section 7, 65 the head 11 is formed with an elongated hub 18, which thus lessens the friction and wear on shaft 1 at the point surrounded by said head.

The heads of the cylinder are made with numerous holes, so as to be sufficiently open to 70 permit water to flow freely from the trough 3 into the cylinder. The water also flows freely between the sections of the cylinder and through perforations in its side.

75 The sections of the cylinder are preferably formed as illustrated in Figs. III, IV, and V. Each section consists of two metal rings, 19, to which are riveted a number of plates, 20, perforated, as shown in Figs. III and V, and having a pyramidal or conical inward projection, 21, pressed therein. I have shown the projection 21 as pyramidal in form; but it is obvious that the conical form may be adopted with good results, one object being to form a surface which inclines toward the edge of 80 the section, as shown in Fig. IV, so that the vegetables being operated upon will roll into the crack between two adjacent sections, and be subjected to the action of both. It will be observed that this figure shows in section the oppositely-inclined grating-surfaces of but two of the grating-rings, (to wit, 7 and 9,) while the section of the other two rings (to wit, 6 and 8) shows no inclination. This is by reason of the fact that the plates 20 (shown in Fig. V) are so 85 secured to the adjacent rings 19 that they will break joints, thereby bringing the summits of the protuberances 21 of one grating-ring in planes between the summits of the protuberances of the adjacent grating-ring. Fig. IV 90 being a section in the plane of the axis of the shaft, it follows that if the said section passes

through the summit of a protuberance on one grating-ring it will pass between two adjacent protuberances on the adjacent grating-ring.

The entire surface of plates 20 and the projections 21 are covered with perforations, as shown, adapting the said plates and projections on adjacent sections of the cylinder to act as graters on different sides of a potato at the same time. The edges of the plates 20, which are next to the cylinder-heads 10 11, are carried onto the inside edges of said cylinder-heads, (see Fig. VI,) thus completing a grating-surface that quickly and effectually removes the skin from the potatoes. The water, rushing through the heads of the cylinder between the sections thereof and through the perforations in the plates 20 and projections 21, keep the said perforations entirely clear of skin.

It will be observed that by making a section 20 of the cylinder, as thus described, any portion thereof can be removed or replaced at pleasure.

One head of the cylinder, preferably that toward the crank 14, is provided with a door, 25 22, opening downward and hinged, as shown, to permit access to the interior of the cylinder for charging with potatoes or removing the same.

The water is drawn from the trough by a 30 plug, 23, as shown in Fig. II.

The spokes 12 are covered with a tin grater-surface, soldered thereto, if preferred.

I am aware that it has been proposed to construct a potato-parer of a pair of oblate hemispherical cups having inwardly-projecting burrs, and provided with interior conical projections having outwardly-projecting burrs, the said cups being placed mouth to mouth and attached, respectively, to a shaft and a 40 hollow sleeve concentric therewith, suitable gearing being provided whereby said cups are rotated in opposite directions about a common axis. Such I do not claim; nor is it the equivalent of my parer, which consists of a cylinder 45 made up of any desired number of sections and means whereby the adjacent sections are rotated about a common axis in opposite directions. In machines of the character to which my invention relates the paring action 50 is produced in greater part (if not wholly) by the action of the oppositely-moving grating-surfaces upon the vegetables being pared; hence the capacity of such a device as above disclaimed, having but two oppositely-moving faces, is necessarily limited, whereas the 55 capacity of my machine may be increased indefinitely by increasing the number of sections of which the paring-cylinder is made up.

Having thus described my invention, the 60 following is what I claim as new therein and desire to secure by Letters Patent:

1. In a potato-parer, the combination, with a plurality of paring-sections and means for rotating them in one direction, of an intervening paring-section and means for rotating it in the opposite direction, substantially as and for the purpose set forth.

2. In a potato-parer, the combination, with a series of rings or circular sections having abrading or grating surfaces and means for 70 rotating them in one direction, of a second series of abrading rings or sections and means for rotating them in a direction opposite to the movement of the first series, the several sections of one series being interposed between 75 the several sections of the other series, substantially as set forth.

3. In a potato-parer, the combination of a series of rings, each having on its interior a grating-surface inclined toward both edges, as 80 shown and described, and means for rotating the adjacent rings in opposite directions, substantially as and for the purpose set forth.

4. The combination, with a rotatable shaft and a grating-section fixed thereto, of a pair 85 of grating-sections located upon opposite sides of the section first named and supported by said shaft so as to turn thereon, and means for turning said pair of grating-sections in a direction opposite to the movement of the section first named, substantially as set forth.

5. In combination with the shaft of a potato-paring machine, a cylinder mounted thereon composed of perforated sections made up of separate plates and each of said plates 95 having an inward projection, substantially as set forth.

6. In combination with the shaft of a potato-paring machine, a sectional cylinder mounted thereon, whose alternate sections are 100 connected by arms or cross-pieces and run loosely on said shaft, while the remaining sections are fixed to the shaft, and suitable gearing whereby each section is revolved in an opposite direction to its neighbor, substantially as set forth.

7. In combination with the supporting-frame of a potato-paring machine and the shaft mounted therein, the sectional cylinder mounted on said shaft, each section having 110 suitable connection with said shaft, whereby they are revolved in opposite directions by the following means, to wit: a pinion mounted on the frame, a gear-wheel on the shaft, and an internally-toothed circular rack rigid with 115 the head of the cylinder, substantially as shown and described.

8. In combination with the shaft of a potato-paring machine, a cylinder having spokes connected with said shaft provided with a 120 rough grater-surface, as set forth.

9. The combination, with the rotatable shaft 1 and the grating-sections 6 and 8, secured thereto, of the head 11, mounted to turn upon said shaft, the grating-sections 7 and 9, connected to said head, the pinion 18, secured to said shaft, and reversing gear connecting said pinion with the head 11, substantially as and for the purposes set forth.

HENRY J. HYER.
